UNITED STATES PATENT OFFICE

104,015

DESIGN FOR A SPECTACLE FRAME

Walter A. Blocker, Larchmont, N. Y.

Application December 31, 1936, Serial No. 66,831

Term of patent 14 years

To all whom it may concern:

Be it known that I, Walter A. Blocker, a citizen of the United States, residing at Larchmont, county of Westchester, and State of New York, have invented a new, original, and ornamental Design for a Spectacle Frame, of which the following is a specification, reference being had to the accompanying drawing, forming part thereof.

Figure 1 is a perspective view of a spectacle frame embodying my new design;

Figure 2 is a front elevational view of the spectacle frame; and

Figure 3 is a top view of the same.

My design is characterized by the type of bridge the temple connections and the comparatively short angular temples, all substantially as shown, in combination with the long narrow lens rims of appreciably greater length than width, each being formed of long upper and lower sides with short vertical sides joined by short oblique sides to the ends of the long upper and lower sides.

I claim:

The ornamental design for a spectacle frame substantially as shown and described.

WALTER A. BLOCKER.
